UNITED STATES PATENT OFFICE.

THOMPSON P. JARVIS, OF SAN FRANCISCO, CALIFORNIA.

OIL-BURNER.

1,107,614.

Specification of Letters Patent. Patented Aug. 18, 1914.

Application filed February 9, 1914. Serial No. 817,522.

To all whom it may concern:

Be it known that I, THOMPSON P. JARVIS, a citizen of the United States, residing in the city and county of San Francisco and 5 State of California, have invented certain new and useful Improvements in Oil-Burners, of which the following is a specification.

The present invention relates to improvements in oil burners, and more particularly 10 to that type of burner which may be readily swung into position into the fire-box or removed therefrom for cleaning or repairing.

The invention is adapted for use in fire-boxes or grates generally, and is particularly 15 adapted for employment in connection with bakers' ovens where a burner which will be clean, safe, will burn without soot or smell, and which may be readily removed, if desired.

20 With the above mentioned and other objects in view the invention consists in the novel construction and combination of parts hereinafter described, and pointed out in the claim hereto appended.

25 Referring to the accompanying drawings—Figure 1 is a view in elevation of my improved oil burner. Fig. 2 is a longitudinal sectional view of the inner swiveled connection which is retained in position by the 30 supporting plate. Fig. 3 is a similar view of the swiveled connection supporting the nozzle, disclosing the needle valve controlling the flow of oil. Fig. 4 is a transverse sectional view taken on line 4—4 of Fig. 3.

35 Referring more particularly to the drawings, wherein like characters of reference designate corresponding parts throughout the several views—1 indicates an elongated swivel joint tapered at its opposite ends and 40 provided in its interior with the chambers 2 and 3, which communicate respectively at their inner ends with the air and oil pipes 4 and 5, through which air and oil is forced under pressure. Suitable castings 6 and 7 45

are positioned over and are adapted to rotate on the opposite tapered ends of the swivel joint and said castings are retained in position to provide a tight joint by the nuts 8 and 9 which are threaded over the 50 threaded studs 10 and 11. A bracket 12

provided with angularly disposed arms 13 is secured to a suitable support, preferably at one side of the opening through which the burner is to be inserted, and said bracket 55 mounts the swivel joint. The arms 13 are formed with suitable bolt openings through

which pass the bolts 14 which are screwed into the studs 10 and 11. The castings 6 and 7 are provided with tubular outlets 15 and 16, and said outlets communicate through the annular channels 15' and 16' with the openings 17 and 18 which communicate respectively with the chambers 2 and 3. Suitable pipes 19 and 20 are threaded into the tubular outlets of the 60 castings 6 and 7 and said pipes carry on their outer ends corresponding castings 21 and 22 which are fitted over the oppositely tapered ends of a swivel joint 23, and are retained thereon to form a tight joint by 65 the nuts 24, which are threaded over studs 25 projecting from the ends of the swivel joint. The interior of the swivel joint is formed with the oil and air chambers 26 and 27, provided adjacent their outer ends 70 with openings 28 and 29, which communicate through the annular channels 30 and 31 in the respective castings 21 and 22 with the pipes 19 and 20.

75 It will be apparent that by forming the 80 castings with annular channels to coöperate with the swivel joint that a communication will at all times be established between the interior of the chambers and the pipes associated with the castings. An air pipe 32 85 is threaded into a nipple 33 projecting outwardly from the swivel joint and said pipe communicates at its inner end with the air chamber 27 and carries at its outer end a nozzle 34 provided with an outlet 35. An 90 oil pipe 36 of smaller diameter than the air pipe is mounted longitudinally therein and the same extends to the nozzle and is mounted at its inner end in an opening 37 in the dividing wall 38 and which opening 95 communicates with the interior of the chamber 26. The oil flowing through the opening 37 is controlled by a needle valve 38' provided with a threaded stem 39 which operates in a threaded casing 40 and carries on its outer 100 end an operating handle 41. A suitable thimble 42 is slidably mounted on the spray nozzle 34 and may be adjusted thereon to regulate the flare of the flame and said thimble is limited in its movement by a 105 collar 43.

110 It will be apparent that the burner has a double swivel support which permits the same to be directed as desired, and is capable of ready insertion into or removal from a fire box or baker's oven, and by mounting the burner on the end of a single pipe a

less opening is required in the furnace door than with the structures now employed. A handle 44 extends from the rear of the swivel joint 23 above the needle valve, and 5 the same assists in the manipulation of the burner.

By constructing my device as above described, it will be observed that the swivel joints 1 and 23 are duplicate castings finished slightly different, and the castings fitted over the tapered ends thereof are duplicates, only of different size, and this form of construction enables the device to be constructed more cheaply than where 10 parts are not interchangeable and provides a device the parts of which may be readily replaced when worn or easily renewed when 15 broken.

Having thus described my invention what 20 I claim as new and desire to protect by Letters Patent is—

A burner of the class described, the same comprising a hollow swivel union tapered toward its opposite ends, a bracket supporting 25 said union at its opposite ends, hollow castings fitted over the tapered ends of said union, said union formed on its interior with separate chambers, an air feed pipe and an oil feed pipe each communicating with one 30 of said chambers and through which the air and oil are forced under pressure, a communication between each of said castings

and one of said chambers, a pair of air and oil pipes secured to said castings, a pair of hollow castings carried by the other ends of 35 said pipes, a hollow swivel union tapered toward its opposite ends and over which said castings are fitted, said union formed on its 40 interior with separate chambers, each communicating with one of said castings, an air discharge pipe carried by said union and extending therefrom in a plane at right angles to the axis of rotation of said union, said pipe communicating at its inner end 45 with the chamber connected to said air supply pipe, a burner carried at the outer end of said pipe, an oil discharge pipe of a diameter smaller than said air discharge pipe and mounted within the same and extending longitudinally thereof, said pipe at its inner 50 end communicating with the chamber connected to said oil supply pipe and communicating at its outer end with said burner, and a valve for controlling the communication 55 between the chamber connected to said oil supply pipe and said oil discharge pipe.

In testimony whereof I have signed my name to this specification in the presence of two subscribing witnesses.

THOMPSON P. JARVIS.
